UNITED STATES PATENT OFFICE.

FRANK R. BENSON, OF KECOUGHTAN, VIRGINIA, ASSIGNOR TO NEWPORT NEWS SHIP-BUILDING & DRY DOCK COMPANY, OF NEWPORT NEWS, VIRGINIA, A CORPORATION OF VIRGINIA.

HOISTING APPARATUS.

Application filed February 9, 1924. Serial No. 691,695.

To all whom it may concern:

Be it known that I, FRANK R. BENSON, a citizen of the United States, residing at Kecoughtan, county of Elizabeth City, 5 State of Virginia, have invented certain new and useful Improvements in Hoisting Apparatus, of which the following is a full, clear, concise, and exact description.

My invention relates particularly to apparatus for hoisting and lowering a plurality of relatively movable parts selectively. 10 The invention is especially applicable to rakes for removing from water racks or screens any form of floating or submerged 15 trash, mud and the like, carried against the same.

An object of my invention is to provide a rapid and efficient means for mechanically controlling a rake of this character, of simple and rugged construction, and which reduces manual labor to a minimum.

Another object is to provide improved means for raising two or more relatively movable members in a predetermined manner, which means are arranged to lock and maintain said members in their raised positions.

A further object of my invention is to provide means for lowering two or more relatively movable members in a predetermined manner.

Other objects and purposes of my invention will appear in the course of the following specification in which I have shown my invention embodied in concrete form for purposes of illustration.

In the drawings illustrating what I now consider the preferred form of my invention,

Fig. 1 is an elevation illustrating my invention as applied to a rack rake, the structural details of the rack and its adjacent structure being omitted to simplify the drawings,

Fig. 2 is a vertical sectional view of Fig. 1, taken on the line 2—2 thereof, an extra line being added to indicate the relative position of the rack,

Fig. 3 is an enlarged detail view of the 50 controlling brake member and one of the clutches, taken on the line 3—3 of Fig. 5,

Fig. 4 is a view similar to Fig. 3, illustrating the brake member and the other clutch, taken on line 4—4 of Fig. 5, and

Fig. 5 is a vertical sectional view of one

of the winding and the clutch members shown in operative relation.

Referring now to the drawings, the numeral 1 indicates a fixed frame or structure for supporting the several operating parts of my invention, which frame is located above the water supply intake, flume or canal, when my invention is used to clean trash racks or screens, so that the movable parts may operate in a vertical plane over the rack in a manner readily understood. The frame 1 is provided at its top with a suitable number of uprights or standards, 2, 3, 4, 5, in which is journaled a shaft 6, having fixed thereon, preferably at its opposite ends the drums 7 and 8 respectively. The standards 4, 5, are also designed to support a motor 9, which is arranged to drive a clutch member 10, through a suitable train of reduction gears, indicated as a whole by the numeral 11. A cooperating clutch member 12, is secured to the shaft 6, but arranged to move axially thereon. A lever 13, pivoted at 14 engages the clutch member 12 by which means the member 12 may be caused to engage the member 10, thereby establishing a driving relation between shaft 6 and motor 9 in a well understood manner. On the shaft 6, and located preferably intermediate the drums 7, 8, is loosely mounted a third drum 15. As shown in Fig. 5, the drum 15 is formed with a rim, which I shall refer to as a brake drum 16, at one end, which forms a part of the braking or control mechanism. Intermediate its axis and said brake drum 16, the drum 15 is also formed with a projection or stop 17, preferably in the shape of a raised segment, of a predetermined size for purposes hereinafter explained, and best shown in Fig. 3. 95

Adjacent the brake drum 16, a similar brake drum 18 is suitably fixed on the shaft 6, having a similar stop 19, best shown in Fig. 4. As shown in Fig. 5, the members 16 and 18 are so arranged that their respective stops will engage so as to form a clutch between said members. A brake-operating lever 20, is pivoted on the frame 1 at 21. At one end, the lever 20 is provided with a weight 22, and at its opposite end with a handle or other operating member 23. The brake drum 16 is engaged by a brake band 24, one end of which is suitably secured to the pin 21 on which the lever 20 is pivoted as shown in Figs. 3 and 5, and the other 110

end of which is secured to the lever 20 at a point intermediate the weight 22 and the pin 21, as shown in Fig. 3. If desired, the brake band 24 may be riveted at one end 5 to a metallic member 25, adapted to receive the pin 21, and at its opposite end secured to another member 26 adapted to fit a threaded member 27, pivotally connected to the lever 20, whereby the tension of the brake band 24 may be adjusted. The brake drum 18 is provided with a similar brake band 28, connected with the pin 21 at one end, and at its opposite end with the lever 20 at a point intermediate the pin 21 and the handle 23. The band 28 may also have parts similar to the parts of band 24, which are given the same reference numerals primed.

A rope 29 on the drum 15 is secured to a 20 vertical frame 30, preferably of metal, by means of an eye piece 31. In its sides the frame 30 is provided with rollers 32, adapted to roll within vertical guides, which usually form a part of the concrete structure 25 through which the water passes, and not indicated in the drawings. The base of frame 30 is formed by an angle iron 33, which is supported thereon slightly in front of the vertical plane of the frame by braces 30 34, as shown in Fig. 2. A rake 35 is pivotally secured to the angle iron 33, such as by hinges 36. The distance the braces 34 support angle iron 33 in front of the sides of frame 30 is such that when the 35 rake 35 moves from its normal vertical position, shown in Fig. 1, and indicated by broken lines in Fig. 2, to its operative position, shown in full lines in Fig. 2, its teeth will either touch or preferably mesh with the rack indicated by the line 36'.

Ropes 37, 38, on the drums 7, 8, respectively, are secured to a horizontal member 39, of the rake actuating mechanism. Rods 40, 41, secured at one end to member 39, 45 pass through the upper side of frame 30, and angle pieces 42, 43, on said frame, respectively, and their free ends are respectively provided with shoulders 44, 45, arranged to limit the upward movement of 50 the rods through the angle pieces. Adjacent and below the shoulders 44, 45, the rods 40, 41, respectively, are provided with links 46, 47, which connect said rods with the rake 35.

Having described the structural details of a preferred form of my invention, its 55 operation will be readily understood from a brief statement thereof. It will be observed that drums 7, 8 are connected with member 39, and the drum 15 is connected to frame 30. Normally, the rake 35 is in a vertical position and the other parts are in the position shown in Fig. 2 in broken lines. The motor 9 is started, and the clutch parts 10, 12 are brought into engage-

ment by moving the handle 13 to the right. Thereupon, the shaft 6 is rotated, turning drums 7, 8, and raising the member 39. By means of rods 40, 41, and links 46, 47, the rake 35 is moved from its vertical position 70 to the horizontal position, indicated in full lines in Fig. 2. This operation requires but a portion of a rotation of shaft 6. During this time, the drum 15, by reason of its loose mounting in shaft 6, is stationary, but the drum 18 is rotating. As the rake 35 assumes the horizontal position, the stop 19, on brake drum 18 is designed to engage stop 17, on brake drum 16, and commences to rotate drum 15, for the purpose of winding rope 29. The frame 30, however, is not raised by the drum 15, but by drums 7, 8, as the shoulders 44, 45 now engage the angle pieces 42, 43, and carry frame 30 upwardly along with the rake 35 in its horizontal position, causing it to pass over the rack 36 and remove trash therefrom, which is removed from the rake manually when it reaches the top of the rack. The frames 39, 30 are locked in their upper position by releasing clutch parts 10, 12 and pulling down on the brake handle 23, which applies the brake band 28 on brake drum 18, thus holding shaft 6 stationary.

After the trash has been removed from the rake, the lowering operation proceeds as follows: The brake handle 23 is released, thereby releasing brake band 28 from brake drum 18, and allowing shaft 6 to rotate, unwinding drums 7, 8 which permits frame 39 to lower. This allows the rake 35 to return to its vertical position, so that when it is lowered, it will pass freely over the rack and not carry any newly accumulated trash down with it. During this time, however, the drum 15 is stationary, it being held by the brake band 24 on brake drum 16, which is applied by the downward action of weight 22. The stop 19 now engages stop 17, and the whole apparatus is held in suspended position with the rake 35 in its vertical position. To lower, it is only necessary to pull slightly on the handle 23, just sufficient to counteract the action of weight 22, which releases brake band 24, allowing drum 15 to unwind, and the whole mechanism to lower. From this it will be seen that the speed of lowering is controlled by the pulling of the brake handle 23, and that the rake cannot drop of its own accord in view of the self-locking features described. It is obvious that an individual handle 23 could be provided for each of the brake bands 24 and 28, if desired.

While I have described my invention as embodied in concrete form and as operating a specific device in a specific manner in accordance with the provision of the patent statutes, it should be understood that I do not limit my invention thereto, since various

modifications thereof will suggest themselves to those skilled in the art without departing from the spirit of my invention, the scope of which is set forth in the annexed claims.

What I claim is:

1. In hoisting apparatus, a rotatable shaft, a brake drum fixed on said shaft, a winding drum loosely mounted on said shaft, a brake drum fixed to said winding drum, and means for limiting the relative movement between said brake drums comprising stops on each of said drums adapted to engage with each other.
2. In hoisting apparatus, a rotatable shaft, a brake drum fixed on said shaft, a winding drum loosely mounted on said shaft, a brake drum fixed to said winding drum, means for limiting the relative movement between said brake drums comprising stops on each of said drums adapted to engage with each other, a controlling member, and brake bands for each of said brake drums connected to said member whereby the brakes may be applied alternately.
3. In hoisting apparatus having a rotatable shaft, a braking device comprising a brake drum fixed on said shaft, a brake drum loosely mounted on said shaft, means limiting the relative movement of said drums to a predetermined amount comprising stops on each of said drums adapted to engage with each other, a pivoted operating member, a brake band operating upon said fixed brake drum secured at one end to a fixed element and at its other end to said member on one side of the pivot thereof, and a brake band operating upon said loose brake drum secured at one end to said element and at its other end to said member on the side of the pivot thereof opposite to which said first brake band is secured.
4. Hoisting apparatus comprising in combination a rotatable shaft, a winding drum fixed thereon carrying a clutch member, mechanism adapted to be raised by said drum, a drum loosely mounted on said shaft having a cooperating clutch member, mechanism connected with said latter drum the movement of which is controlled by said drum, means for alternately braking said clutch members, whereby the positions of both of said mechanisms may be controlled.
5. Hoisting apparatus comprising in combination a rotatable shaft, means for rotating the same, a winding drum fixed on said shaft, mechanism adapted to be raised by said drum, a winding drum rotatably mounted on said shaft, mechanism connected therewith, a brake drum and a clutch member carried by said second-mentioned winding drum, a brake drum fixed on said shaft and carrying a cooperating clutch member, whereby the relative movement of said winding drums and the mech-

anisms connected therewith are limited, brake bands associated with said brake drums, and means for applying the braking force exerted by said bands selectively between said brake drums.

6. Hoisting apparatus for a rack rake comprising in combination a rotatable shaft, a movable structure having a rake pivoted thereto normally in a vertical position, a second movable structure having connections with said rake to place it in a horizontal position when such structure is raised and thereafter raise said first mentioned structure with itself, means on said shaft for raising the second mentioned structure, and means on said shaft for holding both structures in a given position and first lowering the second structure thereby restoring the rake to a vertical position.

7. Hoisting apparatus for a rack rake comprising in combination a rotatable shaft, a frame having a stop thereon and a rake hinged thereto at its base, a second frame connected with said rake to move it about its hinges and having a stop arranged to engage the stop on the first mentioned frame when said rake is swung about its hinges a predetermined distance, means on said shaft for raising said first frame, and means on said shaft for lowering the second frame independently of said first frame a predetermined distance, and a clutch on said shaft arranged to hold both frames in a given position.

8. Hoisting apparatus for a rack rake comprising a rotatable shaft, a winding drum fixed thereon, a frame arranged to move vertically connected with said drum having a stop, a winding drum loosely mounted on said shaft, a second frame arranged to move vertically connected to said loose drum, having a rake hinged thereto adapted to swing from a normal vertical to a horizontal position, and a shoulder adapted to be engaged by the stop when the first mentioned frame is raised, a connection between said first frame and said rake whereby the rake is swung to a horizontal position when the first frame is raised, a brake drum fixed to said loose winding drum, a brake drum adjacent thereto fixed on said shaft, means limiting the relative movement of said brake drums to a predetermined amount, an operating member for said brake drums, and brake bands connecting said brake drums with said member.

9. Hoisting apparatus for a rack rake comprising in combination a vertically movable structure having a rake hinged thereto adjacent its base, a second vertically movable structure connected with said rake to move it about its hinges, means for limiting the relative movement of said structures, a rotatable shaft, means for raising and lowering said second-mentioned structure

as the shaft is rotated, a member rotatably mounted on said shaft and connected to said first-mentioned structure, means for exerting a braking force selectively upon said shaft or said member, and means for limiting the relative rotation of said member with respect to said shaft.

10. Hoisting apparatus for a rack rake comprising in combination a rotatable shaft, a movable structure having a rake secured thereto, a second movable struc-

ture having connections with said rake to move its teeth into position for raking upon movement of such structure and thereafter to move said first-mentioned structure with itself, means on said shaft for moving the second-mentioned structure and means on said shaft for holding both structures in a given position and first lowering the second structure thereby moving the rake teeth towards their original position.

FRANK R. BENSON.
